UNITED STATES PATENT OFFICE

2,031,465

SIGNALING SYSTEM

McKenzie Cottrell, Stratford, Conn., assignor to
General Electric Company, a corporation of
New York

Application December 5, 1934, Serial No. 756,105

7 Claims. (Cl. 250—20)

My invention relates to signaling systems and more particularly to high frequency signal receivers.

In high frequency receivers used in radio reception the intensity of the received signals varies over a wide range dependent upon the distance between the receiver and the transmitter from which signals are being received. In such receivers used for both local and distance reception difficulty is experienced in obtaining optimum quality of reproduced signal during local reception. If the receiver is to be used for distance reception it ordinarily includes a number of high frequency amplification stages, which may include radio frequency stages, a frequency converter stage and intermediate frequency stages, thereby to obtain the desired degree of amplification of the received signal and proper selectivity. The use of such a large number of stages, and particularly the frequency converter stage, reduces the quality of reproduced signal obtained, since each of these stages introduces a slight amount of distortion.

If such a receiver be used for reception from a local transmitting station neither the high degree of amplification or the extreme selectivity obtained by a large number of stages is necessary. Accordingly, it is an object of my invention to provide means whereby certain of said stages may be operatively removed from the receiving circuit during reception of local signals.

A further object of my invention is to provide means whereby the number of stages employed during reception is reduced in response to the intensity of the received signal.

The novel features which I believe to be characteristic of my invention are set forth with particularity in the appended claims. My invention itself, however, both as to its organization and method of operation, together with further objects and advantages thereof, may best be understood by reference to the following description taken in connection with the accompanying drawing in which Fig. 1 represents an embodiment of my invention, and Figs. 2 and 3 represent certain modifications thereof.

Referring to the drawing, I have shown therein a high frequency receiver such as may be used for radio reception which incorporates a pair of antennæ 1 and 2, which may be used for reception of signals of different wave length, and a number of high frequency amplification stages which are conventionally indicated at 3, 4, and 5.

The rectangle 3 may comprise any desired number of radio frequency amplifiers and the rec-

tangle 5 any desired number of intermediate frequency amplifiers, the conventional converter stage 4 being interposed in circuit between these two groups of amplifiers. Rectangle 5 may also represent any desired equipment for producing unidirectional electromotive force for automatic volume control purposes such as an automatic volume control amplifier and detector, the automatic volume control voltage being supplied to the grids of the controlled stages through the conductors designated "A. V. C. conductors" on the drawing. Rectangle 6 indicates the usual local electron discharge oscillator having coupled anode and grid coils 7 and 8 which in the arrangement shown are coupled to the input coil 9 of the converter stage 4 and to the output 10 of the radio frequency amplifier 3.

The second detector of the equipment is indicated at 10' and comprises the usual diode, which operates through a low pass filter 11 into a load 20 resistance 12. Audio frequency electromotive forces which appear on the load resistance 12 may be supplied through audio frequency amplifiers 13 and 14 and transformer 15 to the input circuits of amplifiers 16 and 17. The amplifier 17 is one adapted particularly for amplification of currents of high audio frequency and supplies these currents through an output transformer 18 to a loudspeaker 19, which is likewise adapted more particularly for operation at the high frequency range of voice currents. The amplifier 16 is one designed for operation over the entire voice frequency range but which is not so faithful in its operation at the high audio frequencies as the amplifier 17. Signals supplied through amplifier 16 are reproduced by a loudspeaker 20, which is one adapted more particularly for reproduction of the greater portion of the voice frequency band but the operation of which is less faithful in the high frequency range than the loudspeaker 19.

In the upper portion of the drawing are shown a number of switches 21, 22, 23, 24, 25, 26, 27, 28, 29 which are mechanically connected together for simultaneous operation to form what I prefer to call my high fidelity-high selectivity control means. At the lefthand portion of the drawing is also shown a pair of switches 30 whereby the input to the radio amplifier 3 may be connected either to the antenna 2 for short wave reception, particularly from a distance, or to the antenna 1 for long wave reception.

With the apparatus in the condition shown in the drawing the equipment is adapted for short wave reception and for high selectivity. Signals 55

received upon the antenna 2 are amplified in the amplifier 3 supplied through transformer 9, 10 to the input of the first detector 4. In this input circuit the signals are mixed with the oscillations from the local oscillator 6 to produce in the output circuit of the detector 4 currents of the desired intermediate frequency, which may be the difference frequency between the received oscillations and the oscillations of the source 6. These oscillations are amplified in the intermediate frequency amplifier 5 and rectified by the detector 10', the audio frequency oscillations appearing upon the load resistor 12. These oscillations are amplified by the amplifiers 13, 14, and 16 and the received signals reproduced by the loudspeaker 20. Thus in this position of the fidelity-selectivity control means the receiver has the high selectivity and high amplification afforded by the large number of stages as well as by the superheterodyne action obtained through the converter stage. The signals reproduced, however, are not of maximum fidelity by reason of the presence of the large number of stages.

In this position of the selectivity-fidelity control switches the loudspeaker 19 is short circuited by the switch 29, and accordingly, the high frequency voice currents are reproduced only to the extent of the capabilities of loudspeaker 20. This is desirable in order to eliminate heterodyne squeals when the tuning control is adjusted to positions between stations due to the crowded condition of the broadcast frequency spectrum, and also to reduce, or eliminate, static noises where the receiver has high sensitivity. Accordingly, loudspeaker 19 is effectively removed from the circuit. In addition, these currents may be attenuated by the reactor 31, which is in series with the output of audio amplifier 13, and condenser 32. The effectiveness of this latter condenser may be varied by means of the rheostat 33 whereby the amount of high frequency voice currents transmitted through the amplifier may be varied for "tone control" purposes.

Condenser 32' may also be employed for reduction of the high frequency audio currents. This condenser is connected across the input to the audio amplifier through a variable resistance 33' the movable element of which is mechanically connected with the movable element of potentiometer 12 thereby to reduce the resistance 33' as the volume is reduced. This, in turn, renders the condenser 32' more effective at low volumes of signal. This arrangement is described with greater particularity and claimed in copending application Serial No. 31,274, filed July 13, 1935 by Walter H. Nelson and entitled Combined volume and bass tone compensation control device, which application is assigned to the same assignee as my present application.

If it be desired to receive long waves switches 30 may be moved to their lower position thereby to connect antenna 1 to the receiver.

In the illustrated position the input to direct current amplifier 44 is connected across load resistance 12. This amplifier may include in its output circuit a meter 43 which may be employed for accurate tuning of the receiver.

When the switches 21, 22-29 are operated to their intermediate positions the local oscillator 6 becomes deenergized by action of the switch 24. Switch 23 also applies a positive potential to the cathode of converter 4 thereby making the grid negative with respect to the cathode and rendering this stage completely inoperative even at high R. F. signal levels. By means of switches

22 and 25, the detector 10 is disconnected from the intermediate frequency amplifier and is connected directly to the coil 9, which in turn is coupled to the coil 10. Thus radio frequency signals are supplied directly from the radio frequency amplifier to the detector 10, the converter stage and intermediate frequency amplifier stage 5 being effectively removed from the circuit. At the same time audio frequency amplifier 13 and the tone control network 31, 32, 33 are removed from the circuit by switches 27 and 28, the variable contact on potentiometer 12 being now connected directly to the input of audio amplifier 14. In this position, the short circuit about the loudspeaker 19 is removed by the switch 29 and by means of switch 26 the input to direct current amplifier 44 is now connected to an intermediate point on resistance 12. The purpose of this is to obtain approximately equal input to the direct current amplifier in both positions of the switch. The apparatus is now adapted for reception of strong signals from local stations to obtain the maximum fidelity of reproduction possible and produces a maximum of fidelity. It, of course, now operates without automatic volume control since after the equipment 4, 5 and 6 is disabled, no variable automatic volume control voltage is produced and the bias on the radio frequency amplifiers becomes constant.

When the switches 21, 22-29 are moved to the right all of the high frequency circuits are removed and the input to the amplifier 13 is connected to phonograph equipment 34 for reproduction of recorded signals. In this condition of the equipment the loudspeaker 19 is again short circuited thereby to reduce the reproduction of high frequency currents to avoid "record" scratching sounds.

In Figs. 2 and 3 I have shown modifications of my invention whereby the change from the high selectivity condition to the high fidelity condition and vice versa may be effected automatically. In Fig. 2 I have conventionally indicated switches 21 to 29 as being operated by corresponding electromagnets 21' to 29', the latter being connected in a series circuit which, of course, includes an electromagnet for each of the switches shown in Fig. 1 as indicated by the portions thereof which are dotted. This circuit is controlled by a relay 35 which in turn is supplied with direct current from a direct current amplifier 36. The latter includes in its grid circuit a resistance 37 which in turn is connected between the anode and cathode of a diode 38. The diode is energized from a radio frequency electromotive force which may, if desired, be amplified by a radio frequency amplifier 39 derived from any suitable portion of the radio frequency circuit. For example, the amplifier 39 may have input terminals 40 connected at the terminals 41 of the circuit shown in Fig. 1.

The operation of this form of the invention is as follows: As the signal increases, the voltage on resistance 37 correspondingly increases, thereby driving the grid of electron discharge device 36 increasingly negative and reducing the current flowing in the anode circuit of the discharge device 36. When the signal reaches a certain predetermined value, relay 35 operates to close its contacts, thereby energizing each of the electromagnets 21'-29'. These electromagnets operate the corresponding switches 21-29 and thereby change the receiver from the high selectivity to the high fidelity condition exactly as described in connection with Fig. 1.

Fig. 3 differs from Fig. 2 principally in that in place of the various electromagnets 21'-29' a single electromagnet 42 is employed to operate the various switches 21-29, otherwise the circuit of Fig. 3 differs from Fig. 2 only with respect to the type of bias means employed on the cathode of discharge device 29.

While I have shown particular embodiments of my invention it will of course be understood that I do not wish to be limited thereto since different modifications may be made both in the circuit arrangement and in the instrumentalities employed. I of course contemplate by the appended claims to cover any such modifications as fall within the true spirit and scope of my invention.

What I claim as new and desire to secure by Letters Patent of the United States is:

1. The combination, in a high frequency receiver, of an input circuit, means for converting high frequency currents received in said receiver to currents of different frequency, signal means responsive to said currents of different frequency, and means to disable said first means and to connect said input circuit to said signal means.

2. The combination, in a high frequency receiver, of an input circuit, means for converting high frequency currents received in said receiver to currents of different frequency, means to demodulate said currents of different frequency, a sound reproducing device responsive to the products of said demodulation, and means to disconnect said first means from said detector and to connect said detector to said input circuit.

3. The combination, in a high frequency receiver, of an input circuit, a sound reproducing device, a plurality of high frequency amplification stages, a detector and a plurality of low frequency amplification stages interposed between said input circuit and said sound reproducing device, switching means to disconnect said detector from the output of one of said

stages and connecting it to another stage, switching means to change the number of audio stages between said detector and said sound producing device, and means to operate said switching means simultaneously.

4. The combination, in a high frequency receiver, of an input circuit, a sound reproducing device, a frequency converter stage and a detector stage between said input circuit and said sound reproducing device, and means to disable said converter stage and to connect said detector stage to said input circuit.

5. The combination, in a high frequency receiver, of an input circuit, and a plurality of sound reproducing devices, said sound reproducing devices being adapted for operation over different frequency ranges, a plurality of amplification stages interposed in circuit between said input circuit and said sound reproducing devices, and switching means whereby certain of said amplification stages may be removed from and restored to said circuit, means whereby one of said sound reproducing devices is operatively disconnected from said circuit and restored thereto, and means to operate said last two means to disconnect said certain amplification stages from said circuit and to restore said one sound reproducing device to said circuit simultaneously.

6. The combination, in a high frequency receiver, of a frequency conversion stage, and means responsive to the intensity of the received signal to disable said stage, and means responsive to signals received in said receiver while said stage is disabled.

7. The combination, in a high frequency receiver, of an amplification stage, and means operative in response to a strong signal to disable said amplification stage and to establish simultaneously an operative connection for said receiver.

MCKENZIE COTTRELL.
